UNITED STATES PATENT OFFICE

HERMAN E. MORSE, OF AKRON, OHIO, ASSIGNOR TO THE GOODYEAR TIRE & RUBBER COMPANY, OF AKRON, OHIO, A CORPORATION OF OHIO

DESIGN FOR A HOSE

Application filed June 29, 1931. Serial No. 40,358. Term of patent 14 years.

To all whom it may concern:

Be it known that I, HERMAN E. MORSE, a citizen of United States, residing at Akron, in the county of Summit and State of Ohio, have invented a new, original, and ornamental Design for a Hose, of which the single figure is a perspective view of a section of hose showing my new design.

I claim:

The ornamental design for a hose, as shown.

HERMAN E. MORSE.
